TEXTILE APPARATUS

Ralph H. Balch, Thomas C. Campbell, and James L. Grant, Cumberland, Md., assignors to Celanese Corporation of America, a corporation of Delaware

Application July 1, 1939, Serial No. 282,370

4 Claims. (Cl. 28—40)

This application is a continuation in part of U. S. application Ser. No. 177,212, filed November 30, 1937, now Patent 2,185,621, issued Jan. 2, 1940.

Warping apparatus according to the invention

5 comprises means for driving a warp beam, a plurality of harness shafts disposed between the beam and the yarn supply for guiding yarns to the beam in the form of a plurality of superposed sheets, one sheet for each shaft, means for bringing half of the harness shafts to the same level as each other, means for bringing the remaining half of the shafts to the same level as each other, so that a lease cord may be inserted between the two corresponding sheets of yarn, and means for 10 transposing the two sheets for the insertion of a second lease cord.

Conveniently the levelling of the shafts is effected by the use of stops on connections to the shafts by which the shafts are raised or lowered, 20 the stops being engaged by the means by which the respective sets of shafts are levelled and transposed. Thus, the connections may pass through abutments, one of which is movable and can engage stops to bring the yarns into the plurality of superposed sheets, and through other abutments, one fixed and the other movable, which can engage stops to cause the yarns to fall into two sets, the further movable abutment also being used to transpose its set of yarns with respect to the set controlled by the fixed abutment. After division of the yarns into two sets, the further movable abutment may be moved to increase the space between the sets, thus facilitating the 30 insertion of the lease cords by the usual hooked rod.

The invention will now be described in greater detail with reference to the accompanying drawings, in which

Fig. 1 is a side elevation of the beaming and leasing mechanism;

Fig. 2 is a front elevation of the leasing mechanism;

Fig. 3 is a diagrammatic side elevation of the mechanism in running position, and also showing the creel;

Figs. 4 and 5 are similar to Fig. 3 (omitting the creel) but show the leasing positions of the mechanism;

Figs. 6, 7 and 8 are fragmentary views corresponding to Figs. 3—5, but showing a modification; and

Fig. 9 shows the arrangement of stops and brackets for the shaft arrangement of Figs. 6—8.

55 Referring to Figs. 1 and 3, warp yarns are sup-

plied from bobbins 1, mounted on two 2-bank creels 2, are led over rollers 3 arranged at such a height that the threads can pass as four separate substantially parallel sheets 4 to the warp beam 5. The mechanism includes four heddle shafts 6, 7, 8, 9, and a spacing reed 10 disposed some little distance in front of a roller 11, over which the threads pass to the beam 5. During the winding of yarn on to the beam 5, the shafts 6, 7, 8, 9 occupy the positions shown in Fig. 3, so as to 10 maintain the spaced relationship of the warp sheets 4, thus preventing rubbing of the yarns against each other, the yarns only converging close to the roller 11.

The shafts 6, 7, 8, 9 are carried by a frame 12 extending upwardly from the rear end of the main frame 13 of the beaming mechanism. Each shaft is carried by pairs of cords 14 which pass over pulleys 15 on the top of the frame 12, the cords 14 being connected to rods 16, 17, 18 and 19 20 enabling stops to be connected to the cords, as described below. The rods 16, 17 pass through a bracket 20 fixed to the frame 12, and the rods 18, 19 pass through a movable bracket 21 and a further movable bracket 22. The brackets 21, 22 25 are controlled by cords 23, 24 as will appear below.

Below the bracket 20, the rods 16, 17 have attached thereto stops 26, 27, and the rods 18, 19 have similar stops 28, 29 below the bracket 21. Below the bracket 22 the rods 17, 18, 19 have secured thereto stops 37, 38, 39. With the shafts 6—9 at the levels indicated in Fig. 3, the stops 37, 38, 39 are all contacting with the bracket 22, as in Fig. 1, the stops 37—39 being suitably adjusted on the rods 17, 18, 19 and the stop 26 on 30 the rod 16 for the shafts to hang in this running position. The stop 27 on the rod 17 is, however, spaced from the bracket 20 by an amount representing the difference in height of the shaft 7 above the shaft 6 in Fig. 3. The bracket 21 is 40 positioned so as to contact with the stop 28 on the rod 18 and the stop 29 on the rod 19 is spaced from the bracket 21 by a distance equaling the height of the shaft 9 above the shaft 8, this distance equaling the distance of the stop 27 from 45 the bracket 20.

A counterweight 40 carried by a cord 41 is connected to the larger bracket 22 so that the bracket may readily be brought to different vertical positions. The cords 23, 24 pass round pulleys 42 to 50 levers 43, 44 pivoted at the front end of the frame 13. The tendency of the shafts 6, 7, 8, 9 is to fall under their own weight in the frame 12 and they are also urged downwardly by means of springs 45. The rear ends of the levers 43, 44 are thus 55

urged downwardly, but both levers can be held with their rear ends raised by means of latches. The lever 44 can be latched at positions A and C of Fig. 1 only, while lever 43 is latched only in the 5 D position. The lever 43 can be freely moved between positions A and B. Thus lever 43 is provided with a counterweighted handle 60 which serves to keep the cord 23 taut at all times when the lever 43 is at A or B positions or between the 10 above mentioned positions.

To obtain the first leasing position, as shown in Fig. 4, the operator moves lever 44 in one continuous motion from position A to C. During the first part of this movement, movable bracket 15 22 is raised by the tension of spring 45, an amount equal to the distance shaft 7 is above 6 as shown in Fig. 3. This movement permits rod 17 to rise until stop 27 comes in contact with fixed bracket 20. At this point, shafts 6 and 7 are in the same 20 horizontal plane and remain there during the balance of the leasing operation. At the same time, rods 18 and 19 continue to rise until stopped by lever 43 upon said lever reaching position B and striking a projection or stop at this point. 25 The upward movement of bracket 21 may cease before, at the same time, or after stop 27 comes in contact with fixed bracket 20. The amount of movement of bracket 21 at this point governs the space between the two layers of yarn as shown 30 in Fig. 4 and is controlled by the location of position B.

During the later part of the movement of lever 44 from A to C, bracket 22 is raised by spring 45 attached to shaft 9 through cord 14 and rod 19 35 until stop 29 comes in contact with bracket 21. The counterweight 40 also assists in the upward movement of bracket 22. The distance which stop 29 moves to come in contact with bracket 21 is equal to the distance of shaft 9 above shaft 8 as 40 shown in Fig. 3.

The two sheets are then transposed, preferably after further slight winding of the warps towards the beam 5. This transposition of the warps is effected by operation of the lever 43 only, this 45 lever being fully depressed to lower the bracket 21 and raise the corresponding pair of shafts 8 and 9 by an amount that brings the double sheet of warp controlled by these shafts above the level of the double sheet controlled by the shafts 50 6 and 7, as shown in Fig. 5. Lever 43 is now in position D, (Fig. 1), lever 44 remaining in position C. A further lease cord is inserted between the warps in front of the reed 10, the two cords being separated by the crossing of the threads 55 resulting from the transposition of the sheets from the first leasing position of Fig. 4 to the second leasing position of Fig. 5. The sheets of yarn are then returned to the running position of Fig. 3 by raising the bracket 21 and lowering the 60 bracket 22 to their original positions, as shown in Fig. 1. Levers 43, 44 again occupy position A.

Figs. 6 to 9 show how an operation similar to the one described above can be carried out with a number of shafts greater than 4. In Fig. 6, six 65 shafts 50 a, b, c, d, e, f are shown in running position, to allow the warp to pass as six superposed sheets. The shafts are held in this position by a movable bracket 51, which engages five stops 52 b, c, d, e, f on the connections 53 b, c, d, 70 e, f, and a fixed bracket 54, which engages the stop 55 a on the connection 53 a.

Stops 55 b, c, on the connections 53 b, c, are

spaced from the bracket 54 in the running position by distances equaling the differences in height of the shafts 50 b, c, from that of the shaft 50 a. Stops 55 d, e, f, on the connections 53 d, e, f, lie below a further movable bracket 56, 5 stops 55 e, f, being spaced similarly to the stops 55 b, c.

Raising of the bracket 51 brings the 6 sheets of the warp to 2 levels, as shown in Fig. 7, the bracket 51 and the bracket 56 being further 10 raised, if desired, to increase the spacing between the two sets of sheets. After insertion of the first lease cord, the bracket 56 is lowered to bring the 2 sets of sheets to the position shown in Fig. 8 for the insertion of the second lease cord. 15

Having described our invention, what we desire to secure by Letters Patent is:

1. Warping apparatus comprising means for driving a warp beam, a plurality of harness shafts disposed between the beam and the yarn supply, 20 and means for normally holding the harness shafts at different levels so as to enable them to guide yarns to the beam in the form of a plurality of superposed sheets, one sheet for each shaft, means for bringing half of the harness shafts to the same level as each other, means for bringing the remaining half of the shafts to the same level as each other, so that a lease cord may be inserted between the two corresponding sets of sheets, and means for transposing the two 30 sets of level shafts for the insertion of a second lease cord.

2. Apparatus according to claim 1, comprising means for further separating the two sets of sheets. 35

3. Apparatus according to claim 1, comprising operating connections to the shafts, stops on the connections, means to engage such stops and thereby to position the shafts so that the yarn sheets are superposed, further stops on the connections and means to engage such further stops and thereby bring to common levels the two sets 40 of sheets between which lease cords are to be inserted.

4. Warping apparatus comprising a warp beam, 45 a plurality of harness shafts disposed between the beam and the yarn supply, and means for normally holding the harness shafts at different levels so as to enable them to guide the yarns to the beam, operating connections for supporting 50 the shafts, a movable abutment adapted for the passage of the connections, stops on the connections adapted to engage the abutment and so positioned on the connections that they cause the shafts to guide the yarns in the form of a 55 plurality of superposed sheets, a fixed abutment and a further movable abutment, both adapted for the passage of the connections, further stops on the connections adapted to engage these latter abutments and so positioned on the connections that they cause the shafts to fall into two 60 sets at common levels, means for moving the first movable abutment to allow the fixed abutment and the further movable abutment to be engaged by all their stops, thus separating the 65 yarns into two sets of sheets between which a lease cord may be inserted, and means for moving the further movable bracket to transpose the sets of levelled sheets for the insertion of a second lease cord. 70

CERTIFICATE OF CORRECTION.

Patent No. 2,221,174.

November 12, 1940.

RALPH H. BALCH, ET AL.

It is hereby certified that error appears in the printed specification of the above numbered patent requiring correction as follows: Page 1, first column, line 1, before the words "This application" insert the following paragraph -

This invention relates to textile apparatus and more particularly to warping apparatus provided with means for manipulating sheets of yarn proceeding to a warp beam to permit the insertion of a plurality of lease cords during the warping operation. ;

and that the said Letters Patent should be read with this correction therein that the same may conform to the record of the case in the Patent Office.

Signed and sealed this 10th day of December, A. D. 1940.

(Seal)

Henry Van Arsdale,
Acting Commissioner of Patents.
